UNITED STATES PATENT OFFICE.

ISIDORE STERN, OF NEW YORK, N. Y.

REMOVABLE BRIDGWORK ATTACHMENT.

Application filed November 8, 1920. Serial No. 422,653.

To all whom it may concern:

Be it known that I, ISIDORE STERN, a citizen of the United States, residing at New York, in the county of New York and State of New York, have invented certain new and useful Improvements in Removable Bridgework Attachments, of which the following is a specification.

This invention relates to dentistry, and 10 more particularly to improvements in attachments for use in connection with removable bridge work.

An object of this invention is to produce a new and improved bridge work attachment generally used in the art of dentistry for holding one or more bridge work teeth in position between sound teeth acting as supports.

A primary object is to produce certain 20 improvements in the attachment itself whereby said attachment may be adjusted from time to time to compensate for wear so as to make it tightly fit into sockets formed in the points of support.

25 In practically all types of present day removable bridge work there is no adequate provision to adjust the attachment so it will maintain its original firm setting. My invention overcomes this disadvantage, and

30 provides the wearer with a removable denture which he himself may adjust and keep tight by using any suitable spreading tool. The accompanying drawings form a part of this disclosure and reference is made 35 thereto, wherein:

Figure 1 illustrates an enlarged view of 40 a removable bridge or tooth anchored between the points of support and incorporating this improved adjustable dental attach-

45 Figure 2 shows the three enlarged major projections or views of the removable bridge work attachment separate and apart from the bridge work or tooth it is adapted to support.

50 Figure 3 is a greatly enlarged view showing the improved attachment with a spreader tool inserted therein, and in position to expand the attachment to make it fit more snugly into the supporting sockets.

55 Figure 4 illustrates a cross sectional view taken on line 4—4 of Figure 3 to bring out the cross sectional shape of the spreader tool.

65 Referring more in detail to the drawings for a more comprehensive disclosure of the

invention, there is shown a metal device constructed in accordance with the best principles of dental engineering, and best constructed of a comparatively hard homogeneous metal to resist wear, and possessing the quality of springiness and resistivity so that it will flex and yield slightly to bending and expanding forces. This device comprises a shank 7 made integral on a web 8. The outer edges of the web 8 are bent over and back to form wings 9, and the device is so constructed as to assume a T-shape construction with a hole thru the head or T-part.

The adjacent edges of the wings 9 are brought into close relationship so as to form a nearly uninterrupted plane surface. The opening is formed thru the head of the attachment by virtue of the wings being 70 slightly tapered from a thicker body where the wings join the web out to a thin edge where the wings nearly meet. The opening through the web is triangular shaped which imparts a taper to the wings 9, the 75 said wings being in fact formed by virtue of a split or opening made down through the thin part of the wall formed by the triangular opening.

The attachment, comprising the shank 7 80 and head formation 8—9, is secured to a bridge or tooth 12 in any suitable manner. It is the usual practice to anchor two attachments to the bridge work 12 as shown in Figure 1 which is sufficient to firmly hold 85 the bridge in position between the sound teeth acting as supports for the bridge.

In order to prepare points of support to hold the tooth 12 within the space between the sound teeth 14, it is the usual practice 90 to anchor inlays 15 within the sound teeth as a basis of support for the tooth or bridge 12; and a tube 16, which forms a socket, is embedded in each inlay with an opening or slot in the tube and inlay to admit the shank 100 and head of the attachment. When the bridge work 12, with the integral attachment 7, is placed in position between the two teeth 14, there is formed a permanent and substantial removable bridge tooth to 105 fill the space between the sound teeth, thus providing a full set of teeth.

The advantage of removable bridge work lies in the fact that the bridge may be so constructed and mounted in the mouth that 110 sufficient relative movement may take place between the bridge itself and the sound

teeth, that the disadvantages of immovable and fixed bridge work is overcome; and furthermore the bridge may be removed to be cleaned to maintain the parts in a more sanitary condition than heretofore possible with the old style fixed bridge.

Referring particularly to Figure 3, there is shown a spreader tool having a long tapering blade 18, made on a handle 19, the 10 blade itself being made to fit the opening formed thru the head 8-9. In other words, the blade 18 in cross section is the counterpart of the opening formed in the attachment.

15 The tool is grasped by the handle 19 and carefully thrust into the opening of the head to expand and open the wings to slightly spread them from the web. The blade 18 acting against wings 9 serves to 20 expand and enlarge the head 8-9 of the device. When the bridge 12 is again replaced in between the teeth 14 it is found that it occupies a more firmly anchored connection with the points of support. The head of 25 the attachment may be expanded from time to time by using this tool as above described to make the bridge work fit tightly in position.

A significant advantage of this dental attachment lies in the fact that a skilled dental 30 mechanic or a professional dentist is not necessarily required to make the adjustments. The wearer of the bridge work himself may make the necessary adjustments by carefully pushing and sliding the blade 18 forward into the head of the attachment, and the gradually tapered blade 18 will effectively open out the wings 9 and thus expand the head to make it tightly fit within the 40 tubes or sockets 16. In fact, no specially constructed tool is necessary to make the adjustment for a needle, or any other device sufficiently small and strong to enter the opening and spread the wings is sufficient.

45 The device is simple and inexpensive to manufacture and is characterized by the advantages named, without adding additional expense to the user; and though I have shown one preferred form of construction, I do not limit myself thereto, but claim a right of protection as to obvious changes which come within the scope of my invention.

Having thus described the construction and merits of my invention, what I claim 55 and desire to secure by Letters Patent is:

1. A denture appliance applicable to bridge work where a socket is used as a support for the bridge, said appliance comprising a shank, a web formed on the shank, 60 said web having a triangular shaped hole formed longitudinally therethrough which leaves tapering wing parts expandible by inserting an appropriate tool in the opening whereby the appliance is made to more snugly fit into the socket.

2. A denture appliance applicable to removable bridge work where a socket is used as a support for the bridge, said appliance comprising a member adapted to slide into the 70 socket, said member having a hole formed therethrough in such a manner as to leave one wall uniform in thickness and another wall tapered toward the center, said tapered wall having a split or opening made therethrough which produces a pair of opposed 75 tapered wing parts made on the member, said opposed tapered parts capable of being slightly expanded or bent outwardly which causes the member to more snugly fit with surface contact into the socket, and a shank made on the member by which the appliance is anchored to a dental bridge.

3. A denture attachment for removable bridge work comprising a socket, a shank 80 by which the attachment is anchored to a bridge, a web made on the shank having a hole formed therethrough leaving an outer thin wall, said wall having a split or opening made from end to end thereof to form 85 opposed wing parts integral with the web, said opposed wing parts capable of being uniformly expanded to thicken or make wider the web whereby it takes up for wear and fits more tightly into the socket with 90 surface contact.

4. A denture attachment applicable to removable bridge work where a socket is made in pier teeth to support a bridge, comprising a rectangular shaped member adapted to slide into a socket, a wing formed on opposite parallel edges of the rectangular shaped member to provide opposed wings which have their adjacent edges closely spaced and extending parallel to the vertical axis of the 100 sockets, said wings being slightly expandible to improve the fit and anchoring capacity of the attachment in the socket, and a shank by which the attachment is fixed to the bridge.

5. A denture attachment applicable to removable bridge work where a socket is made in pier teeth to support a bridge, comprising a rectangular shaped member adapted to slide into the socket, a wing 110 formed on the opposed parallel edges of the 115 rectangular shaped member to provide two opposed wings which have their adjacent edges closely spaced and extending parallel to the vertical axis of the sockets, said wings having their meeting edges extending centrally of and parallel to the web, said wings being slightly expandible to improve the fit and anchoring capacity of the attachment in the socket, and a shank 120 by which the attachment is fixed to the bridge.

6. A denture attachment for removable bridgework where a socket is made in pier teeth as a support for the bridge, comprising a web, tapered pieces formed on the web and 125

bent over to leave an open space between the web and tapered pieces, the said web and tapered pieces having their front and back outer wall surfaces ranging in parallel planes, the aforesaid open space adapted to receive a tool to expand the tapering pieces in such a manner that the adjacent edges of the tapered pieces are moved further away from the web but remain parallel to said web and parallel each to each.

7. A denture attachment for removable

bridgework, comprising a head to fit into a socket, and a shank by which the head is anchored to the bridge, said head embodying beveled wings bent over to form a triangular opening thru the head, said opening adapted to receive a tool to bend the bevel wings to increase the size of the triangular opening.

In testimony whereof I hereunto set my hand and seal this 3rd day of November, 1920.

ISIDORE STERN. [L.S.]
